CLAIM

The ornamental design for a soup spoon, as shown and described.

DESCRIPTION

FIG. 1 is a top view of a soup spoon;

FIG. 2 is a left side view of a soup spoon;

FIG. 3 is a front view of a soup spoon;

FIG. 4 is a side front perspective view of a soup spoon; and, FIG. 5 shows a soup spoon contextually within the environment in which the design is used.

The broken lines represent exemplary environmental subject matter and form no part of the claim.

1 Claim, 5 Drawing Sheets
